UNITED STATES PATENT OFFICE

132,859

DESIGN FOR A SAFETY RAZOR GUARD

Carl V. Shipley, Chicago, Ill.

Application April 20, 1942, Serial No. 106,631

Term of patent 14 years

To all whom it may concern:

Be it known that I, Carl V. Shipley, a citizen of the United States, residing at Chicago, in the county of Cook and State of Illinois, have invented a new, original, and ornamental Design for a Safety Razor Guard, of which the following is a specification, reference being had to the accompanying drawing, forming a part thereof.

Figure 1 is a perspective view of a safety razor guard embodying my new design.

Fig. 2 is a transverse sectional view taken on line 2—2 of Fig. 1; and

Fig. 3 is a side elevational view of the embodiment shown in Figs. 1 and 2.

I claim:

The ornamental design for a safety razor guard, substantially as shown.

CARL V. SHIPLEY.
